(57) **CLAIM**

The ornamental design for a faceplate for a manually operable emergency and police vehicle, siren, public address and warning light controller, as shown and described.

DESCRIPTION

FIG. 1 is a front elevational view of a faceplate for a manually operable emergency and police vehicle, siren, public address and warning light controller embodying my invention; and, FIG. 2 is perspective view thereof which shows in dash lines an environment thereof which environment does not form part of our invention.
